Primary Examiner — Charles D Hanson(74) *Attorney, Agent, or Firm* — David G. Rosenbaum; Benjamin D. Rotman; Rosenbaum IP, P.C.(57) **CLAIM**

The ornamental design for a hybrid patterned stent device, as shown and described.

DESCRIPTION

FIG. 1 is a top perspective view of a cylindrically symmetrical hybrid patterned stent device in accordance with a first embodiment of the invention;

FIG. 2 is a left elevation view of FIG. 1;

FIG. 3 is a right elevation view of FIG. 1;

FIG. 4 is a top plan view of FIG. 1;

FIG. 5 is a bottom plan view of FIG. 1;

FIG. 6 is an expanded side elevation view of a flattened section of the hybrid patterned stent device of FIG. 1;

FIG. 7 is a top perspective view of a cylindrically symmetrical hybrid patterned stent device in accordance with a second embodiment of the invention;

FIG. 8 is a left elevation view of FIG. 7;

FIG. 9 is a right elevation view of FIG. 7;

FIG. 10 is a top plan view of FIG. 7;

FIG. 11 is a bottom plan view of FIGS. 7; and,

FIG. 12 is an expanded side elevation view of a flattened section of the hybrid patterned stent device of FIG. 7.
